UNITED STATES PATENT OFFICE

JOHN HERMAN NORLING, OF TOSAKER, SWEDEN

FIRE EXTINGUISHER FOR BENZINE TANKS AND THE LIKE

Application filed March 20, 1929. Serial No. 348,511.

This invention relates to an appliance for supplying extinguishing foam arranged inside a tank for inflammable liquid.

It was hitherto difficult to protect the foam during its passage down to the burning surface in the tank. The devices already known expose the foam more or less to the great heat, the flames and the gases produced by the burning liquid. In consequence, part of the foam was dried by the heat when passing through the fire zone, part of it was thrown out of the tank by whirling, which is most violent at the inner walls of the tank where the heat is greatest, part of the foam dropping down upon the surface of the liquid passed through the said surface on account of the great height of fall and partly disposed, while another part rose to the surface covered with films of oil and was consumed, so that only a trifling portion of the foam remained effective. Experiments made have shown that an effective extinction of inflammable liquids in burning tanks by foam is possible only when the foam is spread out in an unbroken and fresh state over the surface of the liquid.

The present invention that is described below solves, however, the problem of an effective extinction by foam in burning tanks.

The appliance is composed of a plurality of coaxial pipes with longitudinal slots, a foam supplying pipe communicating from above or below with the innermost pipe. Each longitudinal slot is situated on the opposite side of the axis of the pipe to the neighboring pipe. By means of this construction the foam is protected against the action of the gases from combustion until it arrives on the surface of the burning liquid, as these gases, owing to the arrangements of the longitudinal slots, cannot penetrate directly into the innermost of the coaxial pipes, where the foam supplying pipe discharges. The foam therefore flows in the innermost pipe down to the surface of the inflammable liquid without being affected by the gases from combustion and passes through the longitudinal slot of the different pipes and distributes itself over the surface of the liquid.

Two embodiments of the invention are il-

lustrated by way of example in the accompanying drawings, in which:—

Figure 1 shows the first form of construction in vertical section.

Figure 2 is a similar view of the second form of construction.

Figure 3 shows a section on line A—A of Figure 1 on a larger scale.

The appliance consists of two or more coaxial pipes 1 and 2 which are arranged one within the other in such a manner that a space is left between them. These pipes, which are arranged vertically or on an incline in the tank, have each a longitudinal slot 3 and 4, the longitudinal slot 3 of the pipe 1 being situated on the opposite side of the axis of the pipe to the longitudinal slot 4 of the neighboring pipe 2. The foam is supplied to the inner pipe 1 through a foam supplying pipe 5 which can be drawn to the pipe 1 from above or below. The feed of the foam from above comes chiefly into question when the appliance is to be installed in already existing tanks in which the foam supplying pipe mostly enters from above.

In the form of construction illustrated in Figure 1, the foam supplying pipe 5 is introduced into the innermost pipe 1 from below and extends to above the highest calculated level of the inflammable liquid in the tank.

Other forms of construction are possible without departing from the scope of the invention. For example, each of the coaxial pipes may be provided with a plurality of longitudinal slots instead of with one only.

I claim:—

1. An appliance for supplying extinguishing foam inside a tank for inflammable liquid comprising a plurality of pipes arranged one within the other, a space being formed between adjacent pipes, and means for delivering foam to the innermost pipe, each of said pipes being formed with at least one longitudinal slot opening in part above the level of the liquid for the passage of foam.

2. An appliance for supplying extinguishing foam inside a tank for inflammable liquid comprising a plurality of pipes arranged one within the other, a space being formed between adjacent pipes, each of said pipes be-

ing formed with at least one longitudinal slot opening in part above the level of the liquid, and with a foam supplying pipe delivering from below to the innermost pipe 5 and to a point above the calculated highest liquid level of the tank.

3. An appliance for supplying extinguishing foam inside a tank for inflammable liquid comprising pipes arranged one within the 10 other, a space being formed between adjacent pipes, each of which has at least one longitudinal slot opening in part above the level of the liquid, and with a foam supplying pipe that communicates from above with 15 the innermost pipe.

4. An appliance of the type described, comprising coaxial concentric pipes, each coaxial pipe being formed with a longitudinal slot opening above the level of the liquid, the slot 20 of any one pipe being arranged on the opposite side of the axis to the longitudinal slot of the neighboring pipe.

In testimony whereof I affix my signature.

JOHN HERMAN NORLING.
